UNITED STATES PATENT OFFICE.

EMILE AZE, OF MINNEAPOLIS, MINNESOTA, ASSIGNOR OF ONE-HALF TO HANS BJELLAND,
OF MINNEAPOLIS, MINNESOTA.

DIFFERENTIAL MECHANISM.

No. 902,045.

Specification of Letters Patent. Patented Oct. 27, 1908.

Application filed May 15, 1908. Serial No. 432,980.

To all whom it may concern:

Be it known that I, EMILE AZE, of Minneapolis, Hennepin county, Minnesota, have invented certain new and useful Improvements in Differential Mechanisms, of which the following is a specification.

The object of my invention is to provide a differential or compensating mechanism capable of application to vehicles of various kinds but particularly adapted for automobiles and traction engines.

A further object is to provide a simple, positively acting differential mechanism which will allow the wheels and axles to move independently of one another and operate at different speeds.

My invention consists generally in various constructions and combinations, all as hereinafter described and particularly pointed out in the claims.

In the accompanying drawings, forming part of this specification, Figure 1 is a sectional view illustrating the construction of the mechanism. Fig. 2 is a sectional view 25 on the line $x-x$ of Fig. 1. Fig. 3 is a sectional view on the line $z-z$ of Fig. 1. Fig. 4 is a sectional view on the line $y-y$ of Fig. 1.

In the drawing, 2 represents a sprocket wheel having plates 3 and 4 secured thereto by bolts 5 and inclosing the operating portion of the mechanism. The plates 3 and 4 have hubs 6 wherein axles 7 and 8 are journaled and upon which the carrying wheels are mounted in the usual way. At the inner 35 ends of the axles 7 and 8 eccentrics 9 and 10 are formed. A primary cross head 11 is mounted to slide in a guideway 12 provided on the sprocket 2, and the cross head 11 has guideways 13 to receive secondary cross heads 14 and 15. The guideways 13 are at right angles substantially to the guideways 12 and the cross heads 14 and 15 move in a direction at right angles to the direction of movement of the cross head 11. The cross 45 heads 14 and 15 have openings 16 to receive the eccentrics 9 and 10 and the revolution of the eccentrics will cause the cross heads 11, 14 and 15 to be reciprocated in their guideways. The cross head 11 is provided with

brackets 17 wherein levers 18 and 19 are 50 centrally pivoted, said levers having recesses 20 in their ends to receive pins 21 carried by the cross heads 14 and 15 and provided with anti-friction rollers 22. The eccentrics revolve in the sockets 16 and impart a reciprocating movement to the cross heads 11, 14 and 15. One wheel and its axle may turn faster than the opposite one so that one eccentric will overtake the other, and to avoid dead centers when the eccentrics are passing 55 one another the levers 18 and 19 are oscillated to move the cross heads 14 and 15, each lever having a pivotal connection with both cross heads. With this mechanism independent movement of the axles or shafts 7 60 and 8 is permitted, and if one axle moves faster than the other one the cross heads and levers will be operated to compensate for the difference in travel. The eccentrics may be made in various sizes according to the character of the vehicle on which the device is used and the nature of its work.

I claim as my invention:

1. A differential mechanism comprising a gear wheel, a casing secured thereto and having hubs, axles journaled in said hubs and having eccentrics on their inner ends, a primary cross head having a guideway in said gear, secondary cross heads having guideways in said primary cross heads and 75 movable in a direction substantially at right angles to the direction of movement of said primary cross head, said secondary cross heads having openings to receive said eccentrics, and means whereby the movement 80 of one secondary cross head will be transmitted to the other one.

2. A compensating mechanism comprising a gear wheel having a guideway therein, a primary cross head adapted to slide in said guideway and having guideways at right angles substantially to the guideway in said gear wheel, secondary cross heads fitting within said secondary guideways and having openings therein, plates secured to said gear 90 and inclosing said cross heads, axles journaled in said plates and having eccentrics to enter the openings in said secondary cross 95

heads, and levers centrally pivoted on said primary cross head, each lever having a pivotal connection at one end with one of said secondary cross heads and a corresponding connection at its other end with the other of said secondary cross heads, for the purpose specified.

In witness whereof, I have hereunto set my hand this 18th day of April 1908.

EMILE AZE.
